UNITED STATES PATENT OFFICE.

GEORGE A. LEIGHTON, OF MANCHESTER, NEW HAMPSHIRE.

KNITTING-MACHINE.

SPECIFICATION forming part of Letters Patent No. 272,561, dated February 20, 1883.

Application filed August 9, 1880. (Model.)

To all whom it may concern:

Be it known that I, GEORGE A. LEIGHTON, of Manchester, county of Hillsborough, State of New Hampshire, have invented an Improvement in Knitting-Machines, of which the following description, in connection with the accompanying drawings, is a specification.

This invention relates to knitting-machines of the circular class, having two sets or circular series of reciprocating latched needles adapted to knit plain "one-and-one-rib" or to be changed to make the "cardigan stitch," as may be desired.

My improvements in this class of machines consist in the addition of various mechanisms, as hereinafter described, to control the position of the needles and to draw back out of action automatically the horizontal or plate needles, they holding their loops whenever it is desired to bind the edge of the goods, as at the commencement of the cuff of a sleeve, stocking, or other tubular article being knitted.

My invention also consists in certain combinations of mechanism and mechanical devices, hereinafter specifically set forth in the claims at the end of this specification.

Figure 1 is a plan or top view of a knitting-machine containing my improvements; Fig. 2, a side elevation of the same, looking at the machine in the direction of the arrow 1, Fig. 1, part of the frame-work being broken out. Fig. 3 is a vertical sectional detail taken through the spindle and cylinder-needle holder for the cylinder-needles; Fig. 4, a top view of the cam-plate for operating the plate-needles, the levers for operating the cams being omitted, and the said plate being supposed to be transparent, the full lines showing the cams in position for one-and-one-rib work. Fig. 5 is a side elevation of Fig. 1, looking toward it in the direction of the arrow 2, a part of the frame-work being broken away. Fig. 6 is a detail showing the grooved cam-cylinder for moving the cylinder-needles, developed on a plane surface, the switch and cam being in position for cardigan-work; Fig. 7, a detail showing the switch in its other position; and Fig. 8, a detail of the under side of the machine, to illustrate the construction of the shifting device and stops for driving and stopping the shogging motion of the cylinder-needles at the proper place.

The radially-grooved horizontal needle-bed *a*, of usual construction, to contain the series of plate-needles, one of which is shown at *a*², Fig. 1, has applied upon it the cam-plate *b*, provided, as usual, with a drawing-back cam *b*¹ and its actuating-lever *b*², and with the regular throwing-out cam *b*³ and its actuating lever *b*⁴, all as common. The plate *b* is also provided with a cam, *b*⁵, for throwing out the needles in advance, as will be described, for full cardigan-work, and it has a lever, *b*⁶, to move it.

The cylinder-needles *c*, (see Fig. 3, they being omitted in the other figures to avoid confusion,) the cylinder-needle bed *c*', cam-cylinder *c*² to actuate them at the proper times, and spindle *c*³ to support and rotate the said cam-cylinder are common, as in the well-known Aiken circular-rib-knitting machine, except in the cam-grooves and cams and switches of the said cylinder, as hereinafter described as of my own invention. The spindle *c*³ is fixed to the arch *c*⁴ by the set-screw *c*⁵.

Fixed upon the spindle is a dial, *c*⁶, provided with a series of holes (see Fig. 1) to receive suitable pins upon the under sides of spring-handles *d* *e*, to hold the said handles and the parts controlled by them in adjusted position. The handle *d* is connected with a hub, *d*', having a spiral groove, *d*², the said hub being loose on the spindle and receiving a lug at the upper end of the rod *d*³, which at its lower end has attached to it my improved switch *d*⁴, composed of two blocks screwed thereto, fitted into vertical grooves in the cam-cylinder, 85 and provided with an open space between them, the lower end of the upper block being beveled to crowd down the butts of the cylinder-needles at the proper times to shift the needles from the upper groove, 2, into the lower groove, 3, 90 when in the position shown in the detail, Fig. 7.

The upper end of the lower block of the switch *d*⁴ is left square, so that when it is lifted from the position Fig. 7, which is the position it occupies when one-and-one-rib is being knitted with one thread, it will act upon and bodily lift all the needles whose butts are then above it into the upper groove, 2, for cardigan-work, the said switch being shown as so lifted in Fig. 6, after which the succeeding needles 100 of the series of needles are made to travel in the upper groove, 2, for the space leading

down into the groove 3 is closed by the said block. By turning this handle d and hub d' the switch may be raised or lowered, as desired, and be locked in either position. The handle e is suitably connected with the hub e' , having a spiral groove, e^2 , to receive a lug at the upper end of a rod, e^3 , the said rod at its lower end having the usual stitch-regulating or drawing-down cam for the cylinder-needles, 10 the rotation of the hub e' raising or lowering the said cam and permitting it to be locked in any desired position, substantially as in United States Patent No. 197,079, to which reference may be had.

15 Referring to Fig. 6, the cam f , placed next to the drawing-down cam, draws all the needles down far enough to permit the latches of the needles to be closed, as usual, after the hooks are supplied with yarn, but not far enough to 20 cast off the loops on their shanks, as that is the business of the cam e^4 . In advance of this cam f is the auxiliary drawing-down cam f^2 , which is so located as to slightly depress the cylinder-needles in advance of the cams f and e^4 , as the change is being made from cardigan to one-and-one-rib stitch.

When one-and-one-rib-stitch knitting is being done the butts of the needles always travel under cams f^2 f e^4 , along up over the 30 lifting-cam f^3 , along the groove 2, and against the inclined lower end of the upper block of the switch d^4 , and thence into the lower groove, 3; but when cardigan-stitch knitting is being done the butts of the needles pass into groove 35 2 at the right of Fig. 6, and pass always above cam f^2 , thence along under cams f and e^4 , up over cam f^3 , and straight along groove 2, the switches being as in Fig. 6.

The thread-guide g for the plate or horizontal needles, the latch-opener g' for opening the latches of the plate-needles when knitting the one-and-one stitch, and the combined thread-guide and latch-opener g^2 for the cylinder-needles are all as usual in the Aiken machine, 40 with the exception that thread-guide and latch-opener g^2 , is made adjustable by reason of the hole through its shank being slotted or made of greater diameter than the diameter of the bolt which fastens it to the machine, the head 45 of the bolt in the drawings covering, however, the said slot.

The needle-cylinder c' has at its outer side one or more longitudinal ribs, x , to prevent it from rotating, as usual. I utilize the said 55 lugs for shogging the cylinder c' and its needles when knitting the binding course, and to do so I have made the ears or forks n n' movable, having mounted them upon a ring, n^2 . (See Fig. 8.) This ring is provided with a 60 handle, n^3 , having mounted upon it a locking device composed of a spring-pressed pin, n^4 , operated by a lever, n^5 , to withdraw it from holes of an adjustable stop, o , provided with suitable holes, x^2 , and which in practice will be adjustably connected in any suitable or usual 65 way with the needle-bed.

When one-and-one-rib-stitch work is being done the cams of the needle-plate b are all as in full lines, Fig. 4. This needle-plate has connected with it the auxiliary throwing-out 70 cam p , made V-shaped, as shown, and operated to throw it out and in by a pivoted handle, p' , provided with a cam-slot, p^2 , that engages a pin, p^3 , of the cam. This cam is for throwing out certain of the needles a^2 at the 75 commencement of cuff-knitting, or the first course after shogging the cylinder c' of the cylinder-needles for binding off.

In Figs. 1 and 4 the cam-lever p' and the cam p are in the positions they will occupy 80 when placed to so throw out the needles. This handle or lever p' is reversed, as in dotted lines, Fig. 1, to withdraw the cam P , as in dotted lines, Fig. 4, and leave an open space in front of it for the passage of the butts of the plate-needles when it is desired to throw or draw back out of action all the plate-needles preparatory to shogging the cylinder-needles, as set forth. When the lever b^6 occupies the dotted-line position, Fig. 1, and the cam b^5 the dotted position, Fig. 4, the said cam is free to pass the butts of the plate-needles and not actuate them. The change of position of the cam b^6 by its lever b^2 affects only the length of stitch, as usual, and change of position of the cam b^3 95 by its lever b^4 , as usual, throws out the plate-needles a little sooner, as described for fall cardigan-work. The cam-plate b will be rotated by a bevel-gear on a short horizontal shaft, all as usual. The yarn will be supplied from the bobbins s t .

At the front ends of each of the cams b^3 and b^5 , I have inserted lifters w w' to act upon the butts of the needles and carry them forward for a distance about equal to the width of their butts, so that the butts of the needles just behind the points of the said cams b^3 b^5 , when the said cams are being thrown back, will not draw back the needles whose butts then bear on the said cams so far as to cause their loops 110 to be cut off at the inner edge of the plate b ; or, in other words, by the employment of the lifters w w' I am enabled to move the cams b^3 b^5 for a less distance than would be necessary if the said lifters were omitted, for it is 115 obvious that the points of the cams b^3 b^5 must enter a notch or fall behind a shoulder of some kind when thrown outward, and if such shoulder were made in the wall of the groove of greatest diameter the movement of the needles 120 by the cams b^3 b^5 , when moved backward, would be more than when the lifters are used.

To connect a series of tubular articles—such as cuffs and sleeves—together just as the large part of the sleeve is completed, two or more 125 courses of smooth cotton thread are run in preparatory to commencing the cuff of a new or second sleeve, these courses being subsequently withdrawn to separate the cuff of the new sleeve from the large or cardigan part of 130 the old sleeve and leave the cuff bound or finished at its end. A series of cuffs may be

knitted, each connected with the other by the cotton thread referred to.

In this machine the left-hand edge of the switch-cam d^4 (shown in Fig. 6) occupies a position a little forward of the acting outermost corner of the cam b' for the plate-needles shown in Fig. 4, which cam draws back the said needles. The distance between these two cams equals substantially the distance between two needles. The location of the cams d^4 and b' is such with relation to each other that when cam d^4 is to operate in cuff-work it will start to depress the cylinder-needles into the groove 3 as the cam b' starts to draw back the plate-needles.

In cuff-work with one thread, when a cylinder-needle is depressed so that its butt lies in groove 3, the plate needles immediately at the right and left of it are fully drawn back, and hold the loops of plate-needle yarn only in their hooks, thus drawing the plate-needle yarn about the open latches of the cylinder-needles and enabling the same yarn to be engaged by both series of needles. Let it be supposed that the main part of a sleeve has been knitted up to the shoulder by both series of needles, supplied each with its own thread, and operated as usual for the production of full cardigan-work, as, for instance, in United States Patent No. 136,012. If it is desired to make a cuff for a new sleeve, a single thread supplied by the plate-needle-thread guide being then used, the switch d^4 is depressed and the throwing-out cam b^5 is put into its full-line position, Fig. 4, and the machine is rotated until the yarn supplied to the cylinder-needles by the cylinder-needle-thread guide ceases to be supplied to their hooks, the said yarn being broken off, but not removed from its carriers, leaving the machine in condition to do one-and-one or cuff work. I then break off the thread being fed to the plate-needles, and tie upon its end connected with the knitted goods a smooth cotton thread, which is then fed to the plate-needles, and one or more courses are knitted with this cotton thread on the plate-needles. In this condition of the machine the cuff may be commenced. To commence the cuff and manipulate the yarn to be used in the cuff so that the first series of loops may serve as a binding course for the cuff to be knit, I turn the machine part of a revolution and deliver the cuff-yarn in the plate-needle-thread guide (it having been tied to the end of the short cotton thread, one or more courses of which are knitted, as described) into the hooks of the plate-needles, until in the rotation of the machine that one of the horizontal plate-needles next behind the first plate-needle to receive the cuff-yarn is started out, when I stop the machine. Should I continue the rotation of the machine beyond this point without changing the position of the throwing-out cam b^5 , the knitting would be plain one-and-one rib with the thread of the plate-needle-thread guide; but to "bind," as I denominate this first course, I stop the rotation of the machine at this point, draw back the auxiliary throwing-out cam b^5 by its handle p' , and swing its point aside or into the dotted-line position, Fig. 4, so that the butt of the first plate-needle then drawn back and the butts of all the plate-needles drawn back in advance of it in the direction of the rotation of the plate b will be passed by the said throwing-out cam and will not be actuated or thrown out, and the plate-needles so passed over will remain held back out of action in the groove of largest diameter (Fig. 4) and retain their loops. All the needles of the first course at the rear of the first needle passed over by the throwing-out cam b^5 will be drawn back in the regular manner by the cam b' , and the rotation of the machine will proceed until all the plate-needles are drawn back out of action and out of range of the plate-needle-thread guide, when the machine will be stopped, and the grooved needle-cylinder c' , carrying the cylinder or vertical needles c , having on them loops of only the yarn of the plate-needle-thread guide, will be turned axially by the handle n^3 toward the right (see Fig. 8) or left for a distance equal to the space between one and the next plate-needle, the said cylinder-needles so moved or shogged carrying the loops of yarn of the plate-needle-thread guide held by them into positions at the sides of the plate-needles opposite the sides that the said loops occupied before the said cylinder c' was so moved, which action so places the loops of yarn of the plate-needle-thread guide in such a position that when the plate-needles a^2 are again thrown into action the stitch will be such as hereinafter described to bind the cuff. After the cylinder-needles have been shogged aside, as described, the throwing-out cam b^5 for the plate-needles is again moved into its full-line position to operate the plate-needles; but by this cam alone, all the needles being drawn back out of action, as described, I could not knit the first course complete, for those needles the butts of which are left immediately at the rear of the throwing-out cam b^5 , and in the groove of greatest diameter in the plate b , between the cam b^5 and drawing-back cam b' , would not be moved forward to receive yarn from the plate-needle-thread guide; but to obviate this and throw out the said plate-needles left at the rear of the cam b^5 soon enough to receive yarn from the plate-needle-thread guide, I have added an auxiliary throwing-out cam, p , which I move forward into its full-line position, Fig. 4, at the same time that I move the cam b^5 into its full-line position. All the plate-needles being thus properly thrown out into position to receive yarn, plain one-and-one-rib knitting will be done by them and the cylinder-needles with one yarn supplied directly to the plate-needles by the plate-needle-thread guide, and the knitting will be continued until the cuff or article being made is of proper length. While the cuff is being knit by the plate-needles, as described, with one thread, the

thread-guide for the cylinder-needles has its thread disconnected from the fabric, and the cylinder-needles *c* are held so low by groove 3 as to pass under the cylinder-needle-thread 5 guide without receiving yarn therefrom.

If a sleeve or other tubular part with cardigan-stitch is to follow or succeed the cuff, I move the handle *d*, turn cam-hub *d'*, and lift rod *d''* to raise the switch *d''*, which operates 10 the cylinder or vertical needles *c* then just above it, so as to raise or lift up the said cylinder-needles then above its lower flat-surfaced part—usually two or three needles—and place them in the line of the upper groove, 2, in the 15 cylinder; after which the butts of the remaining cylinder-needles in the further rotation of the machine will follow along in the said groove 2, which will hold the cylinder-needles *c* so high, while opposite the drawing-in cam *b'* 20 of the plate-needles, that the cylinder-needles cannot receive yarn in their hooks from the thread-guide *g* of the plate-needles, as they did when knitting one-and-one-rib work. When the cylinder-needles are so lifted into the 25 groove 2 the yarn thereafter supplied to the plate-needles will be drawn by the plate-needles across the shanks of and into the spaces between the adjacent elevated cylinder-needles *c* below their latches. After this the cylinder- 30 needles will be again supplied with yarn from the cylinder-needle-thread guide *g*², the two series of needles, supplied each with its own independent yarn, forming goods having the so-called "cardigan-stitch."

35 In all other machines known to me, when the knitting was to be changed from cardigan (two threads being used) to plain one-and-one-rib stitch, or vice versa, it has always been necessary to adjust or change the position of the 40 thread-guide *g*² for the cylinder-needles to get it out of the way of the cylinder-needles as they are brought into position to do one-and-one-rib work, or to put it into position to supply the elevated cylinder needles *c* with yarn 45 for cardigan-work. This separate adjustment of the cylinder-needle-thread guide *g*², I have done away with by providing the cam-cylinder *c*² for actuating the cylinder-needles with an auxiliary cylinder-needle-depressing cam, *f*², 50 arranged in advance of the usual needle-depressing cam, *f*, it acting to draw down the cylinder-needles sufficiently to obviate striking the cylinder-needle-thread guide *g*².

For full-cardigan work it is necessary to 55 throw the plate-needles *a*² out or toward the center of the machine half the diameter of the machine sooner than when either half-cardigan or one-and-one-rib work is being done, so as to throw outward the said plate-needles and 60 hold them opposite the point where the cylinder-needles *c* are drawing down the loops of their own independent thread, regularly supplied to them by the thread-guide *g*², the plate-needles so thrown out permitting the descending cylinder-needles *c* to draw the thread supplied to them by the thread guide or carrier *g*²

across the shanks of the plate-needles *a*², below their latches, as it has been before described that the plate-needles drew their yarn across the cylinder-needles *c*. 70

In half-cardigan work, two threads being used, as in full cardigan, the yarn supplied to the cylinder-needles is manipulated by the said needles as in regular or plain knitting with only one set of needles; but the yarn supplied to the plate-needles from the plate-needle-thread guide is at such time held about and between the vertical or cylinder needles below their latches, so that as the vertical or cylinder needles descend with loops of their own 80 thread, taken from guide *g*², they draw such loops down through other loops of their own thread then on their shanks below their latches, and at the same time draw the said new loops through the loops of the yarn supplied 85 by the plate-needle-thread guide, the latter yarn being then held (by the hooks of the plate-needles) extended across and between the cylinder-needles, as described, by the hooks of the plate-needles, and both of the said loops are 90 cast off the tops of the cylinder-needles, and the cylinder-needles at the termination of their next upward stroke have each but one loop—viz., that of their own thread—such loop being below their latches. In full-cardigan work, 95 however, the yarn supplied to the cylinder-needles is drawn over, between, and about the plate-needles back of their latches, and the yarn supplied to the plate-needles is drawn about the cylinder-needles below their latches, 100 as in half-cardigan. In full cardigan each needle of both sets of needles has two loops below its latch when descending or drawing in, whereas in half-cardigan the plate-needles have but one such set of loops, they being the 105 loops supplied from the plate-needle-thread guide. In full cardigan both sides of the fabric are alike, the yarn supplied to the cylindrical needles appearing on the inner side of the fabric and that to the plate-needles on the 110 outer side of the fabric; but in half-cardigan work the outside of the fabric is ribbed and the inside is flat.

It will thus be seen that to make cardigan or half-cardigan two independent threads must 115 always be used, each with its own set of needles, each thread having its own carrier, and that in one-and-one rib but one thread is used—viz., that of the plate-needle-thread guide—it being introduced into the hooks of the plate-needles, and drawn about the shanks of the cylinder-needles, which in their descent receive the same thread into their hooks. One-and-one or single rib work presents single longitudinal rows of knitted loops turned in opposite directions, and double-ribbed work presents a series of two adjacent rows of such knitted loops turned in one or the same direction, each series of two loops being separated by a single longitudinal row of loops turned 125 in the opposite direction. In one-and-one work the cylinder-needles adjacent to the plate-nee- 130

dles, being drawn back to form new loops, hold below their latches loops of yarn previously supplied by the plate-needle-thread guide, and the cylinder-needles as they descend by action of cam e^4 draw the new loops of yarn laid on their latches, as before described, down through the loops so held on their shanks below their latches, thus forming new loops from the yarn of the plate-needle-thread guide.

The spindle c^3 , with which the cam-cylinder forecylinder-needles is connected, may be raised and lowered by hand-manipulation to make the rib more or less prominent without necessitating the adjustment of the switch and stitch-regulating cam, the screw c^5 during such movement being loosened by a suitable wrench.

I claim—

- 20 1. In a circular-knitting machine, a series of plate and cylinder needles, and the regular throwing-out cam to operate the plate-needles, combined with the auxiliary throwing-out cam to throw out only the plate-needles at the rear of the regular throwing-out cam, the said auxiliary cam throwing out the said needles to receive yarn and knit during that course of knitting next after shogging the cylinder-needles, substantially as described.
- 25 2. The cam-plate for the plate-needles, provided with the usual needle-actuating cam-grooves, combined with the cams b^3 b^5 and the lifters w w' to obviate excessive backward movement of the butts of the plate-needles in contact with the said cams when they are moved, to thereby obviate cutting the loops held by the said needles when shogging the cylinder-needles and binding the cuff, substantially as described.
- 30 3. The cam-cylinder provided with the grooves 2 3 for the cylinder-needles, combined with the drawing-down cams e^4 f , and with the auxiliary drawing-down cam f^2 to draw down the cylinder-needles in advance of the act of the usual drawing-down cams, to thereby lower the said needles out of the way of the thread-guide for the cylinder-needles when knitting one-and-one-rib work, substantially as described.
- 35 4. In a knitting-machine, the series of plate-needles and means to operate them, the cylinder-needles, and the cam-cylinder provided with the cam-grooves 2 3 to actuate the cylinder-needles, combined with the switch d^4 , its rod and grooved hub to raise and lower the said switch at the proper times, to enable the machine to knit either cardigan or plain one-and-one rib, substantially as set forth.
- 40 5. In a knitting-machine, a series of plate-

needles and cylinder-needles, the cam-cylinder 60 for the cylinder-needles provided with the grooves 2 3, the stitch regulating cam, the needle-lifting cam and switch, and the carrying-rods for the switch and stitch-cam, and the adjustable spindle upon which the said cam-cylinder is held, combined with the arch to hold the spindle and permit it to be raised and lowered to make the rib more or less prominent, and with the rotating grooved hubs to adjust or change the position of the switch and stitch-regulating cams independently of the movement of the spindle, as set forth.

6. The series of plate-needles, their holding-bed, and cam-plate b , provided with the movable cams b^5 , p , b' , and b^3 , and cylinder-needles, their holding-bed and cams to move them, and two independent thread-guides, combined with the arm n^3 , a suitable movable support therefor, and stops to regulate the extent of movement of the said arm, the said arm being 80 adapted to engage the bed of the cylinder-needles and shog or move the said bed to place its needles at the opposite sides of the plate-needles, substantially as and for the purpose set forth.

7. In a knitting-machine, the bed for the plate-needles, and the bed for the cylinder-needles, provided with lugs, combined with the ring having the two forks to embrace the two lugs at the opposite sides of the said bed and 90 turn it axially to shog the cylinder-needles, and with a lever to turn the said ring and forks, and with stops to regulate the extent of axial movement of the said ring and bed, as and for the purposes set forth.

8. The bed for the plate-needles, the series of plate-needles, means to operate them, the bed for the cylinder-needles, lugs thereon, the cylinder-needles, the cam-cylinder provided with two cam-grooves, 2 3, to actuate the cylinder-needles, and the switch d^4 , its rod and grooved hub to raise and lower the said switch at the proper times, combined with the ring having the two forks to embrace the two lugs of the bed for the cylinder-needles and turn it 105 axially to shog the cylinder-needles, and with a lever to turn the said ring and forks, and with stops to regulate the extent of axial movement of the said ring and bed for the cylinder-needles, as and for the purposes described.

In testimony whereof I have signed my name to this specification in the presence of two subscribing witnesses.

GEO. A. LEIGHTON.
